UNITED STATES PATENT OFFICE.

JOSEPH DUGGAN, OF PAINESVILLE, OHIO.

HINGE-FASTENER.

1,186,528.

Specification of Letters Patent. Patented June 6, 1916.

Application filed September 7, 1915. Serial No. 49,179.

To all whom it may concern:

Be it known that I, JOSEPH DUGGAN, a citizen of the United States, residing at Painesville, in the county of Lake and State 5 of Ohio, have invented new and useful Improvements in Hinge-Fasteners, of which the following is a specification.

This invention relates to hinge attachments and particularly to the means for attaching door hinges to the casing, the objects of the invention being the provision of a fastener that is simple and inexpensive, that strengthens the hinge, that prevents the sagging of the door, protects the casing, and 15 that expedites the hanging or removing of the door.

The present invention is especially serviceable in its application to screen doors which are in use only a portion of the year, 20 as the door, equipped with the improved device, can be easily and quickly detached from the casing, the entire hinge remaining attached to the door and leaving the casing free from unsightly projections, and providing equal convenience in reattaching the 25 door in exactly the same position it formerly occupied.

The improvement also provides a stop which relieves the strain on the hinge, and 30 can be made adjustable, thereby adapting it to different sizes or types of hinge.

The invention consists in an alinement plate or plates provided with tongues and co-acting with bushed screw sockets and a 35 thumb-screw, the sockets registering with the screw holes in the attaching leaf of the hinge, whereby the hinge may be readily attached to or detached from the casing, as will be clearly understood from the following 40 specification, reference being had to the accompanying drawings in which similar characters of reference are employed to designate similar parts.

In the drawings Figure 1 is a view in elevation of a portion of a door frame and casing with an ordinary hinge attached thereto with the improved fastener. Fig. 2 illustrates the relative position of the door to the casing when the door is completely 50 open, showing certain of the parts in section. Fig. 3 is a view of a fragment of the

casing, showing two types of screw socket. Fig. 4 is a section on line 4—4 of Fig. 3, with washer members added. Fig. 5 is a perspective view of one form of alinement plate. 55 Figs. 6 and 7 are perspective views of bushings or screw sockets. Figs. 8 and 9 illustrate a washer in plan and edge view, respectively. Fig. 10 is a view in elevation of one butt of a hinge, showing the position of the adjustable fastener. Fig. 11 is a view in direction of arrow in Fig. 10. Fig. 12 is a perspective view of one of the adjustable alinement plates.

As the principal utility of the present invention consists in the attachment of a hinge to the casing, the following description will be confined to the casing and the elements connected therewith, briefly stating that the hinge member 1 may be attached to the door 70 frame 2 with screws 3 in the ordinary manner.

In order to get the best result or in other words to obtain the full benefit of the invention, it is of course necessary that the 75 first hanging of the door is given careful attention, which is a matter of good craftsmanship, thereafter the door may be easily and quickly attached to or detached from the casing innumerable times by any one not 80 familiar with the art of door hanging.

In the practical application of the invention, bushing members are set into the casing 4. A preferred form of bushing 5 has a more or less coarse external thread 6 and a 85 transverse slot 7 in the end thereof, whereby it can be threaded into the casing with a screw-driver.

8 represents a bushing member provided with a shank 9 and a flange 10 which may be 90 attached to the casing by the prongs 11 or by screws 12, both of which may be employed or either one or the other eliminated. It will readily be seen that either form of bushing may be used, as the function is the 95 same. The bushings are provided with a threaded bore 13, and are positioned in the casing with the mouth of the bore registering with the eyes 14 and 14^a in the hinge member 15. While it is only necessary that 100 the bore of one of the bushing members be threaded, it is preferable to thread them all

as a matter of convenience, making them interchangeable. To enhance the appearance of the casing when the bushings 5 are used and the hinge is removed, they are countersunk as shown, and washers 16 provided with prongs 17 are let in flush with the face of the casing.

The attachment member or alinement plate 18 may be made in one piece as shown in Figs. 1, 2, and 5, in which case it is made to conform in certain dimensions to a standard type of hinge. In the embodiment of the invention illustrated, the hinge member 15 is provided with two outer eyes 14, 14 and an intermediate eye 14^a. The member 18 has tongues 19 that are adapted to pass through the outer eyes 14, 14 and penetrate the bores of two of the bushings in the casing, thereby alining the hinge with the casing, assuming of course that the bushings are properly located relative to the hinge. A hole 20 is provided in the plate member 18, and when the tongues 19 are seated in the outer eyes 14 and their corresponding bushings, the hole 20 registers with the intermediate eye 14^a and its corresponding bushing bore. A thumb-screw 21 is threaded into the intermediate bushing through the opening 20 and completes the fastening of the hinge to the casing. The plate 18 also acts as a reinforcement to the attaching flange 15, thereby strengthening the hinge. When the door is opened the head of the thumb-screw, or the wings 22 thereon come in contact with the hinge member 1 and thereby prevent straining or breaking the hinge or its connections with the door or casing.

It will readily be seen that the adjustable fastener illustrated in Figs. 10, 11, and 12 is merely a modification of that above described, the casing attachments being identical and the functions of the other parts being the same. In the modification the alinement member is in two parts 18^a, 18^a, each of which is provided with a tongue 19^a, corresponding in function to the tongues 19 of the member 18. Slots 20^a in the members 18^a are the equivalent of the hole 20 in member 18. The plates 18^a overlapping and the shank of the thumb-screw passing through the slots and threaded into the intermediate bushing in the casing perform the same function as the corresponding parts in the non-adjustable device. The two part alinement member provided with the slots 20^a admits of the adjustment of the fastener to hinges of various sizes, as the plates may be shifted to accommodate the tongues 19^a to different spacings of the eyes in the hinge leaf, and the slots admit the registering of the thumb-screw with the holding socket and its corresponding eye in the leaf.

While I have shown and described a practical embodiment of my improvement it will be understood that departure from details of construction, design and arrangement of the several parts may be made without departing from the nature of the invention, the limitations being governed by the scope of the claims and the existing state of the art.

Having now described my invention, what I claim and desire to secure by Letters Patent is—

1. A hinge fastener comprising an alinement member consisting of one or more plates adapted to be placed on the exterior of the attaching leaf of a hinge and provided with tongues that pass through said leaf and penetrate the body to which the hinge is to be attached, an opening in said alinement member, and a screw which passes through said opening and the attaching leaf and is threaded into said body.

2. A hinge fastener comprising an alinement member consisting of one or more plates adapted to be placed on the exterior of the attaching leaf of a hinge and provided with tongues that pass through said leaf and extend into registering bushings in the body to which the hinge is to be attached, an opening in said alinement member, and a screw which passes through said opening and the attaching leaf and is threaded into a bushing in said body.

3. A hinge fastener comprising an adjustable alinement member, said member consisting of two plates adapted to be placed on the exterior of the attaching leaf of a hinge and provided with tongues that pass through said leaf and penetrate the body to which the hinge is to be attached, a slot in each of said alinement plates, and a screw which passes through said slots and the attaching leaf and is threaded into said body.

4. A hinge fastener comprising an adjustable alinement member, said member consisting of two plates adapted to be placed on the exterior of the attaching leaf of a hinge, each of said plates provided with a slot, and tongues that pass through said leaf, in combination with bushing members in the body to which the hinge is to be attached, the said tongues extending into said bushings; a screw which passes through the slots in the alinement member and through the attaching leaf of the hinge; and an internally threaded bushing in the body, into which said screw is threaded.

5. In a hinge fastener the combination of screw sockets threaded into the body to which the hinge is to be attached and registering with holes in the attaching leaf of the hinge; washers at the mouths of said sockets; an alinement member consisting of one or more plates provided with an opening

and adapted to be placed on the exterior of the attaching leaf of the hinge; tongues on said alinement member that pass through the attaching leaf of the hinge and through the washers into registering screw sockets; a screw which passes through the opening in alinement member, through the attaching

leaf of the hinge and is threaded into one of the screw sockets.
